Inventor:
George S. Tiffany
by his Atty:
Philip Payne Richardson

UNITED STATES PATENT OFFICE.

GEORGE S. TIFFANY, OF SUMMIT, NEW JERSEY, ASSIGNOR TO TELAUTOGRAPH CORPORATION, OF RICHMOND, VIRGINIA, A CORPORATION OF VIRGINIA.

TELAUTOGRAPHIC APPARATUS.

1,326,994.

Specification of Letters Patent.

Patented Jan. 6, 1920.

Application filed December 15, 1917. Serial No. 207,284.

To all whom it may concern:

Be it known that I, GEORGE S. TIFFANY, a citizen of the United States, residing at Summit, county of Union, and State of New Jersey, have invented certain new and useful Improvements in Telautographic Apparatus, fully described and represented in the following specification and the accompanying drawings, forming a part of the same.

This invention relates to improvements in telautographic systems of the kind in which the writing currents traversing the main lines, between the transmitting instrument and the receiving instrument, are varied in strength by the lateral or writing movements of the transmitting tracer, and, as thus varied, cause the receiving pen to reproduce the movement and writing performed by the transmitting tracer.

The present improvements have particular reference to the provision between one station (which may be called the home station) and several distant stations, of a receiver-selecting mechanism under the control of the operator of the transmitting instrument at the former, whereby he can, at will, select and connect with his transmitting instrument the receiving instrument of any of the distant stations, and which is also under the control of the operator at the receiving stations, whereby the operator at any of the latter can connect his transmitter with the receiver of the home station.

The operation of the receiver-selecting mechanism referred to from the home station is effected by impulses of different quality, and preferably of opposite polarity, traversing the main lines and the sending of which is controlled by a receiver-selecting switch mechanism at the home station, while the operation of the receiver-selecting mechanism from the distant stations is controlled preferably by the writing current traversing one of the main lines and which is controlled by the master switches of such stations.

The present improvements also contemplate the provision of certain specific means operable by the operator of the home station for controlling this receiver-selecting mechanism, and means which, on the connection of any transmitter with another, will lock

the others against operation, and notify the operators thereof that the line is busy.

The invention comprises other features which will be hereinafter more particularly described, in connection with the accompanying drawings in which—

Figure 1 is a diagrammatic view illustrating what may be termed a master station A, including a transmitting instrument and a receiver, and illustrating also a selecting mechanism B from such master station to a group of distant receivers C, D, E, F.

Fig. 2 is a diagrammatic view illustrating two stations, the receivers whereof are controlled by said receiver-selecting mechanism, so that any one of said receivers may be connected with the transmitting instrument of Fig. 1 at the will of the operator at the latter, and the transmitters whereof also control said receiver-selecting mechanism, so that such transmitters may be connected, at the will of the operators thereof, with the receiver of the master station; and

Fig. 3 is a view similar to Fig. 2, illustrating two additional stations controlled by such receiver-selecting mechanism.

Referring to said drawings—1 represents a battery which is the source of electric energy for the writing currents from the transmitter of Fig. 1 to the receivers of Figs. 2, 3, and whereby the movements of any selected distant receiver are effected and controlled by the transmitting instrument of Fig. 1; the neutral point of this battery being grounded by wire 2, at 3. 4, 5 represent a pair of rheostats, and 6, 7 a pair of contact rollers contacting therewith, respectively. These rollers 4, 5 are carried by suitably pivoted arms 8, 9, which are in turn connected (so as to be swung thereby lengthwise of their respective rheostats) with a pair of bell-crank levers 10, in the converging ends of which is mounted a transmitting tracer 11; all as is well understood. The enlarged terminals of rheostats 4, 5 are connected, by wire 12 for the former, and wires 13, 14 for the latter, and a common wire 15 and wire 2, with the neutral of battery 1 and ground at 3. The other ends of the rheostats 4, 5 are connectible by wire 16, for the former and wire 18 for the latter, and a common wire 19, switch contact plate

20, master lever 21, and wires 22, 23 with the positive pole of battery 1. Normally switch lever 21 is raised from the position shown in Fig. 1, and moved to the position 5 shown in Fig. 1, as it is desired to connect the transmitter of station A with the receiver of station C, D, E or F, it not only effects the engagement of itself with contact 20 to connect the rheostats 4, 5 with the 10 positive pole of battery 1, but also effects the engagement with each other of other contacts (hereinafter referred to and constituting, with lever 21 and contact 20, a master switch mechanism,) which connect 15 the rheostats 4, 5 with the right and left main line circuits to the distant receivers.

As the master switch lever 21 is shown in Fig. 1, the rheostats 4, 5 are connected with the positive of battery 1, and it will be understood that as the tracer 11 (which is shown out of normal or unison position) is moved laterally or sidewise, as in ordinary writing, the contact rollers 6, 7 will be moved, through bell cranks 10 and arms 8, 25 9, lengthwise of their respective rheostats 4, 5, with the result that, as their positions change lengthwise of these rheostats, currents of greater or less strength will be shunted from the positive pole of battery 1 30 into the right and left main line circuits, from the transmitting instrument of Fig. 1 to the selected distant receiver of stations C, D, E, F and the local receiver 24 of Fig. 1.

In the case of the local receiver 24, the 35 right main line circuit consists of contact roller 7, arm 9, wire 25, switch members 26, 27 (which are held in contact by master switch lever 21) and wires 28, 29 to the right hand coil of a pair of rectilinearly movable 40 pen-moving coils (not shown), in receiver 24, such as are commonly used in telautographs of the present day; while the left main line circuit consists of contact roller 6, arm 8, wire 30, contact 31, switch member 32, 45 and wires 33, 34 to the left-hand pen-moving coil of the receiver 24. This receiver has the usual pair of pen arms 35 in the converging ends of which is mounted a receiving pen 36. In these respects, and otherwise, this receiver is of the ordinary, well-known construction, so that further illustration or description of it is unnecessary. It will be understood that, as in the well-known telautograph, as the tracer 11 is 50 moved laterally in writing and the contact rollers 6, 7 moved thereby longitudinally of their respective rheostats, and currents varying in strength are thus caused to traverse the right and left main line circuits just described, the receiving pen 36 will be caused to move in unison with tracer 11 and reproduce the writing movements and writing performed thereby. This is true also of each of the distant receivers illustrated in 55 Figs. 2 and 3.

In the case of the receivers 40, 41, 42, 43 of the distant stations C, D, E, F, the right main line circuit from the transmitter of station A (Fig. 1) consists of contact roller 7, arm 9, wire 25, switch members 26, 27 70 (held in contact by switch lever 21) wire 28 and wires 45, 46, the latter (wire 46) being connected by wire 47, with the usual right-hand pen-moving coil of receiver 40, and by wires 47^a, 47^b, 47^c with the usual 75 right-hand pen-moving coils of receivers 41, 42, 43, respectively. The left main line from the transmitter of station A to the receivers 40, 41, 42, 43 of stations C, D, E, F, consists of contact roller 6, arm 8, wire 30, contact 31, switch member 32, wire 33 and wires 80 50, 51, to certain parts of the receiver-selecting mechanism B, which will be herein-after fully described, and thence by wires 54, 54^a, 54^b, 54^c, to the left-hand pen-moving 85 coils of receivers 40, 41, 42, 43, respectively.

It will be noted from the foregoing that the main line currents from battery 1 of station A to the distant receivers 40, 41, 42, 43, for operating the latter, are always positive 90 currents; that the right main line circuit 46 from the transmitter is always connected (for a purpose hereinafter stated) with said several distant receivers when a writing current traverses right main line 46 from battery 1; and that the left main line circuit 51 *et seq.* to said several receivers is normally disconnected, at the receiver-selecting mechanism B, from said receivers, the closing of such main line circuit to such receivers being controlled by receiver-selecting switch mechanism, operable from the transmitter of station A, which will now be described.

The receiver-selecting mechanism B of 105 Fig. 1 comprises four pick-up relays 55, 55^a, 55^b, 55^c, one for each of the left main line branches 54, 54^a, 54^b, 54^c, for the receivers 40, 41, 42, 43, respectively, and four polarized relays 56, 56^a, 56^b, 56^c. Relays 56, 56^c 110 are connected by wire 57, and by wire 58, between them, with right main line wire 46, and with ground at 59 by wires 60, 61; while relays 56^a, 56^b are connected with left main line wire 51 by wire 62 and by wire 115 63, between them, and with ground at 59 by wires 64, 61. Relay 56 is energized by a negative impulse from battery 1 over right line 46 and controls the closing of a local circuit from the positive of a local battery 120 65 through pick-up relay 55; relay 56^a is energized by a negative impulse from battery 1 over left line 51 and controls the closing of a circuit from local battery 65 125 through pick-up relay 55^a; relays 56, 56^b, 56^c acting together and energized respectively by negative and positive impulses from battery 1 over right and left main lines 46, 51, control the closing of a local circuit from battery 65 through pick-up relay 55^b; and 130

relays 56^a, 56^c, acting together and energized, respectively, by negative and positive impulses from battery 1 over left and right main lines 51, 46, control the closing of a local circuit from battery 65 through pick-up relay 55^c.

These four local circuits for the different pick-up relays 55, 55^a, 55^b, 55^c, together with the means controlling polarized relays 56, 56^a, 56^b, 56^c to open and close them, are as follows:

For relay 55, the local circuit from battery 65 consists of wire 70, armature 71 of polarized relay 56, upper contact 72 therefor (to which it is moved when a negative impulse traverses right main line 46 from battery 1), wire 73, armature 74 of relay 56^c, lower contact 75 therefor, wire 76, part of wire 54, wire 77, pick-up relay 55, wire 78, armature 79 of relay 55, contact plate 80, and wires 81, 82, 83, 84, to the negative of battery 65 and to ground at 59. Contact plate 80 is of the follow-up type, with relation to the armature 79 of relay 55—that is to say, it is held depressed by the armature 79 and moves with it when the latter is attracted by its relay 55 and continues doing so until it is arrested as hereinafter described. This is true also of like contact plates connected with the armatures of the other pick-up relays 55^a, 55^b, 55^c.

For relay 55^a, the local circuit from battery 65 consists of wire 70, wire 85, armature 86 of relay 56^a, upper contact 87 therefor (to which the armature 86 is moved when a negative impulse traverses left main line 51 from battery 1), wire 88, armature 89, of relay 56^c, lower contact 90 therefor, wire 91, wire 92, part of wire 54^a, relay 55^a, wire 93, armature 94 of relay 55^a, contact plate 95, and wires 96, 81, 82, 83, 84 to the negative of battery 65 and ground and closes the local circuit described.

For relay 55^b, the local circuit from battery 65 consists of wire 70, armature 71, of relay 56, upper contact 72 therefor (to which the armature 71 moves when a negative impulse traverses the right main line 46), wire 73, armature 74 of relay 56^b, upper contact 98 therefor (to which the armature 74 is moved when a positive impulse traverses the left main line 51), wires 99, 100, part of wire 54^b, relay 55^b, wire 101, armature 102 of relay 55^b follow-up contact plate 103, and wires 104, 81, 82, 83, 84, to the negative of battery 65 and to ground.

For relay 55^c, the local circuit from battery 65 consists of wires 70, 85, armature 86 of relay 56^a, upper contact 87 therefor (which armature 86 engages when a negative impulse traverses the left main line 51), wire 88, armature 89 of relay 56^c, upper contact 105 therefor (which is engaged by armature 89 when a positive impulse traverses right main line 46), wires 106,

107, part of wire 54^c, relay 55^c, wire 108, armature 109, contact plate 110, and wires 111, 82, 83, 84, to the negative of battery 65 and ground at 59.

From the foregoing description of the four local circuits for pick-up relays 55, 55^a, 55^b, 55^c, and polarized relays 56, 56^a, 56^b, 56^c, and the connection of these relays with the main line wires 46, 51, it will be observed (1) that when a negative impulse from main battery 1 traverses right main line 46, pick-up relay 55 will be energized and attract its armature 79; (2) that when a negative impulse traverses left main line 51, pick-up relay 55^a will be energized and attract its armature 94; (3) that when a negative impulse and a positive impulse from battery 1 simultaneously traverses the right and left main lines 46, 51, respectively, pick-up relay 55^b will be energized and attract its armature 102; and (4) that when a negative impulse and a positive impulse simultaneously traverse the left and right main lines 51, 46, respectively, pick-up relay 55^c will be energized and attract its armature 109.

The effect of all this in selecting distant receivers and connecting them to the transmitter of Fig. 1, is as follows:—It will be observed that each of the pick-up relays 55, 55^a, 55^b, 55^c is equipped with a follow-up contact plate 115, 116, 117, 118, respectively, each of which, like the follow-up contact plates 80, 95, 103, 110, respectively, previously referred to, follows the movement of the armature of its relay, and as said armature is attracted by the relay, moves upwardly with it. Referring particularly to the relay 55, the contact plate 115 thereof continues such movement until its outer end engages a stationary contact 120 which arrests its movement and also that of contact plate 80. The effect of this is to disengage armature 79 from contact plate 80 and thereby break the local circuit from battery 65 through relay 55, and at the same time (by the engagement of contact plate 115 with contact 120) connect main line wire 51 (by wires 121, contact plate 115, contact 120) with main line wire 54 leading to receiver 40 of station A (Fig. 2). This local circuit is maintained open, and the connection between main line wires 51, 54, held closed, by means of a spring-pressed latch 122 pivoted at its upper end at 123, and the lower end of which slips over the tail end of pivoted armature 79 so as to retain it in the position to which it is moved by relay 55.

When pick-up relays 55^a, 55^b, 55^c are energized, their respective local circuits from battery 65 are broken and left main line wire 51 connected with receivers 41, 42, 43, respectively. In the case of relay 55^a, main line wire 51 is connected, by wire 124, con-

tact plate 116, contact 125 and wire 92, with main line wire 54^a to receiver 41; in the case of relay 55^b main line wire 51 is connected, by wire 126, contact plate 117, contact 127 and wire 100, with wire 54^b leading to receiver 42; and in the case of relay 55^c main line wire 51 is connected, by wire 128, contact plate 118, contact 129, and wire 107, with wire 54^c leading to receiver 43. For each of the armatures 94, 102, 109, of relays 55^a, 55^b, 55^c, there is provided a spring-pressed pivoted latch 130, 131, 132, like latch 122 of relay 55.

All of the four latches 122, 130, 131, 132 are pivotally connected together intermediate of their ends by a link 133, so that when any one of them is rocked rearwardly on its pivot 123, that is to say, away from its relay, by the upward movement of the armature of that relay, all the other latches will be correspondingly moved. The result of this is that should any of these latches, at the time, be in latching engagement with the armature of its relay (as shown in the case of latch 122 and armature 79 of relay 55) it will be disengaged therefrom, and the armature be permitted to drop away from its relay, into the position shown in the case of armature 94 of relay 55^a, for example. This breaks engagement between contact plate 115, 116, 117 or 118, as the case may be, and contacts 120, 125, 127, 129, and disconnects main line 51 from main lines 54, 54^a, 54^b or 54^c, as the case may be, to receivers 40, 41, 42, 43, respectively. In other words, the arrangement is such that when the operator of station A selects any one of the distant receivers and connects it with the transmitter of station A, any other receiver which may at the time be connected with the latter transmitter, is automatically disconnected therefrom. The receiver-selecting switch mechanism provided at the transmitter for controlling distant receiver-selection and connection will now be described.

The transmitting instrument of Fig. 1 is provided with a magnet 135, having two armatures 136, 137, and with a selecting switch mechanism consisting of two single switches 138, 139, each having a single contact plate and two double switches each having two contact plates 140, 141 and 142, 143, the contact plates of each pair being suitably insulated from each other. The magnet 135 is in a circuit tapped off the left main line wire 50 and consisting of wire 145 therefrom, and wires 146, 2, to the neutral of battery 1 and ground at 3. Normally the master switch lever 21 is raised and the several master switch contact plates disengaged, so that there is no writing current from battery 1 on the right and left main lines. In this condition magnet 135 is de-energized and its two armatures 136, 137 rest against their back stops 147, 148, where

they form parts of branch circuits connecting the two main line wires 46, 51, with the positive and negative of battery 1, and the closing of which is controlled by the switches 138, 139, 140 and 141, 142 and 143. 70

The circuit controlled by switch 138 consists of wire 150 from the negative of battery 1, armature 137, contact 148, wires 151, 152, 153, contact plate 138, contact 154, and right main line 46 to polarized relays 56, 56^a. 75 When switch 138 is moved by the operator at the transmitter to engage contact 154 (Fig. 1), an impulse of negative polarity will traverse the right main line 46 through polarized relay 56, the armature 71 of which 80 is thereby moved to its upper contact 72, thus closing the local circuit previously described from local battery 65 through pick-up relay 55, with the result that receiver 40 (station C) will be connected with the 85 left line 51 from transmitter of Fig. 1 and remain so connected by reason of the engagement of latch 122 with the tail of armature 79 of said relay, as before described. 90 This receiver-selecting circuit is also controlled by the contact plates 141, 143 of the double switches 140, 141 and 142, 143, as will presently be described.

The circuit controlled by switch 139 consists of wire 150 from the negative of battery 1, armature 137, contact 148, wires 151, 152, 155, contact plate 139, contact 156, and left main line wire 51 to relay 56^a. On the closing of this circuit, by the engagement of switch 139 with contact 156, a negative impulse from main battery 1 traverses the left main line 51 through polarized relay 56^a, the armature 86 of which is thereby moved into engagement with contact 87 and thus closes the local circuit before described 100 from battery 65 through pick-up relay 55^a, with the result that left main line wire 51 is connected with main line 54^a to the receiver 41 of station D (Fig. 2). This receiver-selecting circuit is also adapted to be 110 closed by the members 140, 142 of the two double switches 140, 141 and 142, 143, as presently described.

To connect receiver 42 of station E (Fig. 3) with the transmitter of Fig. 1, the double switch 140, 141 will be utilized. When moved to the left of Fig. 1, its contact plates 140, 141, will engage contacts 157, 158, respectively. Such engagement will connect right main line wire 46 with the negative 115 pole of battery 1, through wire 150, armature 137, contact 148, wires 151, 159, contact plate 141, contact 158 and wires 160, 161, and will connect the left main line wire 51 with the positive pole of battery 1, through wires 23, 162, armature 136, contact 147, wires 163, 164, contact plate 140, contact 157 and wire 165. A negative impulse will therefore 125 traverse the right main line 46 through polarized relay 56 and, simultaneously there- 130

with, a positive impulse will traverse the left main line 51 through polarized relay 56^b. The former will cause the relay 56 to attract its armature 72 and the latter will 5 cause the relay 56^b to attract its armature 74, thus closing the local circuit through pick-up relay 55^b and, with the result, as before stated, that receiver 42 will be connected with the left main line 51 from the transmitter.

To connect receiver 43 of station F (Fig. 3) with the transmitter of Fig. 1, switch 142, 143 is moved to the left of Fig. 1 into engagement with contacts 166, 167, respectively. Right main line 46 is thus connected with the positive of battery 1 through wires 23, 162, armature 136, contact 147, wire 163, contact plate 142, contact 166, and wires 168, 161, and left main line wire 51 is connected 20 with the negative of battery 1 by wire 150, armature 137, contact 148, wires 151, 169, contact plate 143, contact 167 and wires 170, 165. On the simultaneous closing of these 25 circuits a positive impulse will traverse the right main line 46 through polarized relay 56^c and a negative impulse will traverse the left main line 51 through polarized relay 56^a; the effect of this being, as before stated, to close the local circuit from battery 65 30 through pick-up relay 55^c and, through the contact plate 118 and contact 129 with which said relay is equipped, connect left main line wire 51 with left main line wire 54^c to receiver 43.

When the desired receiver of distant stations C, D, E, F, as the case may be, has been thus selected and connected with left main line 51 from transmitter of station A, by manipulation of the proper receiver-selecting switch 138, 139, 140—141 or 142—40 143 the master switch lever 21 will be depressed, to the position shown in Fig. 1, to engage the several sets of contact plates of the master switch mechanism with each 45 other and thus connect the right and left main lines of the transmitter of station A with the positive pole of battery 1, through rheostats 4, 5, as shown in Fig. 1. This transmitter and the selected receiver are 50 then ready for the transmission of messages from the former to the latter. In this position of switch lever 21 also magnet 135 is energized by the circuit before referred to, bridged across the left main line and ground, and consisting of wire 145, magnet 135, wire 146, and wire 2 to ground at 3. The magnet 135, energized thereby, will 55 attract its armatures 136, 137, and open the two branch receiver-selecting circuits just described from the negative and positive poles of battery 1, so that these circuits cannot be closed by switches 138 *et seq.* while writing currents are traversing the main lines. When master switch lever 21 is raised to 60 normal position (in which position it is

locked by the spring-pressed armature 172, of a magnet 173, which engages the insulated end of lever 21), these receiver-selecting circuits are automatically re-established (subject to closing by the switches 138, 139, 140—141 and 142—143) by the release and retraction of armatures 136, 137.

At each of the stations C, D, E, F, there is provided a battery 174 (the negative pole of which is grounded at 175 by wires 176, 177) and an electro-magnet 178, connectible with the positive pole of said battery by a circuit consisting of wires 179, 180, armature 181, of magnet 178, contact 182, and wires 183, 184, 177, to ground at 175. This circuit 80 includes an electric lamp 185 which when the circuit is closed by the movement of armature 181 into engagement with contact 182, is lighted to indicate that the line is busy. The energization of magnet 178 to 85 effect the movement of armature 181 is controlled by a circuit 186, 187, 184, bridged from right main line 46 to earth at 175, so that when a writing current is on the right line 46, magnet 178 is energized and attracts 90 its armature 181. The closing of this lamp circuit occurs not only in the case of the station including the receiver selected but also in the case of all other stations, the right main line 46 being always connected 95 with all of the stations (including their magnets 178), on the movement of master switch lever 21 to the position shown in Fig. 1, so that the attendants at the several stations not selected will know that the distant transmitter is busy with one of the stations. The magnets 178 and their armature 181 also perform other functions which will now be described.

For convenience of description, the distant stations C, D, E, F, have thus far been dealt with as equipped with receivers only but, as shown in the drawings, each of them is also equipped with a transmitting instrument identical with that of master station A, except that, unlike the latter, it is not provided with receiver-selecting switch mechanism, though it is provided with master switch mechanism, whereby it may be connected with the receiver of station A. 105 Selecting for detailed description station C, the transmitter thereof includes the usual tracer arms 190, 191, and levers 192, 193, in the converging end of which is mounted transmitting pen 194 (shown at station C, 110 Fig. 2). Arms 190, 191, carry contact rollers 195, 196, engaging rheostats 197, 198. One end of rheostat 197 and the corresponding end of rheostat 198 are connected by wires 200, 201, 202, contact plate 203, switch lever 204 (when depressed), and wires 205, 179 with the positive pole of battery 174; while the other ends of said rheostats are connected by wires 206, 207, 177, 176 with the negative of battery 174. Switch lever 204 is the 115 120 125 130

controlling element of a master switch mechanism, including the contact plate 203, which coacts with said lever 204, and two additional pairs of contacts 208, 209 and 210, 211. Contact 208 is connected by wire 212 with main line wire 46, and contact 209 by wire 213 with arm 191 and right-hand-rheostat 198, while contact 210 is connected by wire 214 with left main line wire 54, and contact 211 by wire 215 with arm 190 and left-hand rheostat 197. When, therefore, master switch lever 204 of station C is depressed, it engages contact 203 and connects the positive of battery 174 with rheostats 197, 198, while contacts 208, 209 connect arm 191 and rheostat 198 with right main line 46 to station A, and contacts 210, 211, connect arm 190 and rheostat 197 with left main line wire 54 to the pick-up relay 55 of the receiver-selecting mechanism. The effect of the engagement of contacts 210, 211, is to temporarily close a circuit from battery 174 through pick-up relay 55 consisting of the connections just described, ending with wire 25 54, and thence by wire 77, relay 55, wire 78, armature 79, contact 80 and wires 81, 82, 84 to ground at 59. This causes relay 55 to attract its armature 79 and break contact between it and contact plate 80, thus opening 30 this circuit. Latch 122, however, will engage armature 79 and retain it in its upper position and the follow-up contact plate 115 will engage stationary contact 120, and thus, through wire 121, connect left main line 35 wire 54 with left main line wire 51. Any of the other armatures 94, 102, 109 (stations D, E, F) that may be, at the time, held in its upward position by its latch 130, 131, 132, will be automatically released by latch 40 122 which, when swung rearwardly by the upward movement of armature 79, will move link 133 to the right (Fig. 1) and said rod will in turn swing each of the latches 130, 131, 132, to the right, so that they will release the armatures 94, 102, 109, if in their 45 upper position, and permit them to drop to the positions shown in Fig. 1. The contact plates 116, 117, 118, associated with these armatures also drop away from contacts 125, 127, 129, and thus disconnect left main line wires 54^a, 54^b, 54^c (or such of them as may 50 then be connected therewith) from left main line wire 51.

When switch lever 204 is closed, right main line is closed from the positive of battery 174 of station C by wires 179, 205, switch lever 204, contact 203, wires 202, 201, right rheostat 198, roller contact 196, arm 191, wire 213, contacts 209, 208, wires 212, 46, 45 and 29 through the usual right hand pen-moving coil in receiver 24 of the master station A (Fig. 1). The left main line circuit is also closed from the positive of battery 174, by wires 179, 205, switch lever 204,

contact 203, wires 202, 200, left rheostat 197, 65 roller contact 195, arm 190, wire 215, contacts 211, 210, wires 214, 54, contacts 120, 115, wires 121, 51, 50, 34 through the left-hand pen-moving coil of receiver 24.

Tracer 194 being then moved from its 70 unison position, writing currents will traverse the right and left main lines from battery 174, through rheostats 198, 197, to the receiver 24 of station A. The writing current traversing right main line 46 will, 75 through a circuit consisting of wires 29, 216, 217, 15, 2, to ground at 3, energize magnet 173 of station A, which will thereupon attract its armature 172. The latter will then slip over the insulated tail end of switch 80 lever 21, which is then in its raised or normal position (the reverse of that shown in Fig. 1), and lock it against movement downward to connect the several contacts of the master switch. The effect of this is to lock 85 out the transmitter of station A while the transmitter of the distant station C is in writing connection with receiver 24. Magnet 173 also, through its armature 172, controls a lighting circuit consisting of wires 90 23, 218, armature 172, contact 219, and wires 220, 221, 217, 15, 2, from the positive pole of battery 1; this circuit, which includes a lamp 222, being closed in the forward position of armature 172, so that the operator 95 in charge of station A is notified (by the lighting of lamp 222) that one of the distant stations is in writing connection with receiver 24.

The foregoing description, although directed specifically to the transmitter and connections of station C, is equally applicable to the transmitters and connections of stations D, E, F. For convenience in applying such description to these other transmitters and connections, the same reference numerals have been applied thereto as to the transmitter and connections of station C. 100

In addition to performing the function of lighting lamps 185, so as to indicate to the 110 operators at the several distant stations C, D, E, F, that the transmitter of master station A is busy with one of them, the magnets 178, also, through their armatures 181, and the engagement of the latter with the insulated tail ends of master switch levers 204 (then in their raised or normal positions) lock the transmitters of the distant stations C, D, E, F, out of writing connection with the receiver 24 of station A. 120 Similarly when one of the transmitters of stations C, D, E or F, is in writing connection with receiver 24 of station A, the transmitter of that station is not only locked out of operation, but the transmitters of the other three distant stations, are also locked out, by the writing current traversing the 125 right main line 46 with which each of the

magnets 178 is connected, as heretofore described with particular reference to the transmitter of station A.

What is claimed is:

each branch for retaining the connection when made with its main line wire, and connections between the latches of the several branches whereby when one branch connection is made, others previously made are broken.

8. The combination with a home station having a transmitter, a receiver, and a master switch, a plurality of distant stations each having a transmitter, a receiver, and a master switch, and main line wires from the home station, one provided with separate branches to the distant stations, of a receiver-selecting switch mechanism in the home station effecting the sending of impulses of different quality over the main line wires, relays connected with and dependent for action upon the quality of the impulses traversing the main line wires, local circuits controlled by said relays, other relays in said local circuits controlling the connection of the branches aforesaid with their main line wire, whereby the home transmitter may be connected with any of the distant receivers, and connections between the master switches of the distant stations and said branches, local circuits and last named relays whereby, when any of said master switches is closed, the distant transmitter corresponding thereto is connected with the home receiver.

9. The combination with a home station having a transmitter, a receiver, and a master switch, a plurality of distant stations each having a transmitter, a receiver, and a master switch, and main line wires from the home station, one provided with separate branches to the distant stations, of a receiver-selecting switch mechanism in the home station effecting the sending of impulses of different polarity over the main line wires, polarized relays connected with and dependent for action upon the polarity of the impulses traversing the main line wires, local circuits controlled by said relays, other relays in said local circuits controlling the connection of the branches aforesaid with their main line wire, whereby the home transmitter may be connected with any of the distant receivers, and connections between the master switches of the distant stations and said branches, local circuits and last named relays whereby, when any of said master switches is closed, the distant transmitter corresponding thereto is connected with the home receiver.

10. The combination with a home station having a transmitter, a receiver, and a master switch, a plurality of distant stations each having a transmitter, a receiver, and a master switch, and main line wires from the home station, one provided with separate branches to the distant stations, of a receiver-selecting switch mechanism in the home station, operative when the master

switch thereof is open and inoperative when it is closed, effecting the sending of impulses of different quality over the main line wires, relays connected with and dependent for action upon the quality of the impulses traversing the main line wires, local circuits controlled by said relays, other relays in said local circuits controlling the connection of the branches aforesaid with their main line wire, whereby the home transmitter may be connected with any of the distant receivers, and connections between the master switches of the distant stations and said branches, local circuits and last named relays whereby, when any of said master switches is closed, the distant transmitter corresponding thereto is connected with the home receiver.

11. The combination with a home station having a transmitter, a receiver and a master switch, a plurality of distant stations each having a transmitter, a receiver and a master switch, a continuous main line wire, normally connecting the home station and each of the distant stations, and another main line wire from the home station provided with separate branches to the distant stations, of a receiver-selecting switch mechanism at the home station, a receiver-selecting mechanism controlled thereby and by the master switches of the distant stations, whereby the home transmitter may be connected with any of the distant receivers and any of the distant transmitters connected with the home receiver, a magnet in each of the stations connected with the continuous main line aforesaid, and devices controlled by said magnets for locking the master switches against closing movement whereby, when the master switch of one station is closed, the master switches of all other stations are so locked.

12. The combination with a home station having a transmitter, a receiver and a master switch, a plurality of distant stations each having a transmitter, a receiver and a master switch, a continuous main line wire, normally connecting the home station and each of the distant stations, and another main line wire from the home station provided with separate branches to the distant stations, of a receiver-selecting switch mechanism at the home station, a receiver-selecting mechanism controlled thereby and by the master switches of the distant stations, whereby the home transmitter may be connected with any of the distant receivers and any of the distant transmitters connected with the home receiver, a magnet in each of the stations connected with the continuous main line aforesaid, and indicator circuits controlled by said magnets whereby when the master switch of one station is closed, the fact is indicated at all other stations.

13. The combination with a home station having a transmitter, a receiver and a master switch, a plurality of distant stations each having a transmitter, a receiver and a master switch, a continuous main line wire, normally connecting the home station and each of the distant stations, and another main line wire from the home station provided with separate branches to the distant stations, of a receiver-selecting switch mechanism at the home station, a receiver-selecting mechanism controlled thereby and by the master switches of the distant stations, whereby the home transmitter may be connected with any of the distant receivers and any of the distant transmitters connected with the home receivers, a magnet in each of the stations connected with the continuous main line aforesaid, indicator circuits and master switch locks controlled by said magnets whereby, when the master switch of one station is closed, the fact is indicated at all other stations and the master switches of the latter locked against closing movement.
14. The combination with a transmitter, a master switch therefor, a plurality of receivers, and main line wires from the transmitter, of a receiver-selecting mechanism, a switch mechanism therefor, and connections between said switch mechanism and the master switch whereby, when the latter is closed, the former is inoperative.
15. The combination with a transmitter, a master switch therefor, a plurality of receivers, and main line wires from the transmitter, of a receiver-selecting mechanism, a switch mechanism therefor, including circuits having a plurality of circuit closers, a plurality of hand-operated switches, and a magnet controlling said circuit closers, and connections between said magnet and the main line whereby, when the master switch is closed, said circuit closers are opened.
16. The combination with a transmitter, a master switch therefor, a plurality of receivers, and main line wires and connections from the transmitter to the receivers, of a receiver-selecting switch mechanism effecting the sending of impulses of different quality over the main line wires, receiver-selecting mechanism controlled thereby and in turn controlling the connection of the transmitter with the receivers, and connections between the said master switch and switch mechanism whereby when the master switch is closed the circuits controlled by the switch mechanism are opened.
17. The combination with a transmitter, a master switch therefor, a plurality of receivers, and main line wires and connections from the transmitter to the receivers, of a receiver-selecting switch mechanism effecting the sending of impulses of different polarity over the main line wires, receiver-selecting mechanism controlled thereby and in turn controlling the connection of the transmitter with the receiver, said selecting mechanism including polarized relays controlled by such impulses, and connections between the said master switch and switch mechanism whereby when the master switch is closed the circuits controlled by the switch mechanism are opened.
18. In a selective switch system, the combination of a home station, a plurality of other stations, selecting mechanism electrically connected with all of said stations, means controlled at said home station for electrically operating said selecting mechanism, whereby the writing circuits of a telautograph at the home station may be connected to the writing circuits of a telautograph at any of the other stations, and means for preventing the operation of telautograph transmitters when their writing circuits are not connected to the home station through said selecting mechanism.
- In testimony whereof, I have hereunto set my hand.

GEORGE S. TIFFANY.
